GARAGE DOOR

Filed Nov. 5, 1928

UNITED STATES PATENT OFFICE

WILLIAM D. FERRIS, OF STERLING, ILLINOIS, ASSIGNOR TO FRANTZ MANUFACTURING CO., OF STERLING, ILLINOIS, A CORPORATION OF ILLINOIS

GARAGE DOOR

Application filed November 5, 1928. Serial No. 317,178.

This invention relates to garage doors, or doors for other buildings, and more particularly to doors of this kind, that are adapted and constructed to move upwardly out of the doorway, or other opening, and into an open position overhead, or into a position at the top of the opening.

Generally stated, therefore, the object of the invention is to provide a novel and improved construction whereby the door, or other closure, is composed of sections hinged together and mounted to fold into open position at the top of the doorway, or other opening, whereby to obviate the necessity of employing overhead tracks, or rails, or guides, and whereby other advantages are obtained, as will hereinafter more fully appear.

It is also an object to provide certain details and features of construction and combinations tending to increase the general efficiency and desirability of an overhead folding door or closure of this particular character.

To the foregoing and other useful ends, the invention consists in matters hereinafter described and claimed and shown in the accompanying drawing, in which—

Figure 1 is an inside view or rear elevation of a garage door construction involving the principles of the invention, showing adjacent portions of the doorway and the front wall of the building;

Figure 2 is a vertical section on line 2, 2 in Figure 1, the door being shown in closed position in these two figures of the drawing;

Figure 3 is a view similar to Figure 2, but showing the door in open position;

Figure 4 is an enlarged detail horizontal section on line 4, 4 in Figure 1;

Figure 5 is an enlarged vertical detail section on line 5, 5 in Figure 1.

As thus illustrated, the invention comprises a plurality of horizontally disposed door sections 1, 2 and 3, disposed in the same vertical plane, the upper section 1 being connected by hinges 4 to the stationary portion 5 of the doorway. These hinges 4 are preferably of such construction that they have some lost motion therein, permitting the pivots thereof to move slightly up and down, some

upward displacement being necessary when the sections 1 and 2 are pushed inwardly in starting the opening movement of the door. The sections 1 and 2 are connected together by outside hinges 6, and the section 2 may be provided inside with a hinged or folding handle 7. If necessary or desirable, a similar handle 8 can be provided on the outer side of the section 2 of the door. The sections 2 and 3 are hinged together by means of the inside hinges 9, and the section 3 may have an outside handle 10 for use in pulling the door down into closed position.

The hinges 9 have sheaves 11 traveling in the vertical guides 12, disposed at opposite sides of the doorway and, in addition, these sheaves have suitable portions for engaging the counterbalance cords or connections 13, which latter have their lower ends attached to the section 3 at 14, and have their upper portions supported by stationary sheaves 15 mounted in the doorway frame, or in the structure of the building, each cord having a counterweight 16 for its other end, as shown.

The sections of the door rest firmly against the inside of the door-jamb 17, when the door is in closed position, and, in addition, the lower section 3 is held tightly by the inside strips or inner jamb 18, as shown in Figure 2 of the drawing. When the door is in closed position, the weights 16 are incapable of pulling the door up into open position.

However, when it is desired to open the door, it is only necessary to take hold of the handle 7 and pull the sections 1 and 2 inwardly, which movement causes section 3 to slide upwardly in the plane thereof. When the door is thus partially opened, and when the section 3 has been disengaged from the inner jamb 18, the weights 16 are then operative to fold the door sections together and pull the door into open position, as shown in Figure 3 of the drawing.

To close the door, it is only necessary to reach up and grasp the handle 10 and pull the sections downward until the lower edge of the section 3 is between the outside jamb 17 and the inside jamb 18, and by then pushing on the sections 1 and 2 from the inside,

the door structure will be straightened out in the manner shown in Figure 2 of the drawing and will thus be closed.

It is obvious, of course, that a door of this kind can be locked either from the outside or from the inside, in various ways, depending upon conditions and requirements. In some cases, it may be desirable to unlock the door and open it from the outside, but if the garage has a rear door, the overhead folding door may then be unlocked and opened from the inside.

As shown, the door comprises three sections hinged together, but it will be understood that the invention is not limited to any particular number of sections, nor to the exact construction shown and described.

With the foregoing construction and mode of operation, which is illustrative of one form of the invention, it will be seen that no overhead tracks, or rails, or guides, are necessary, inasmuch as the door has no sliding movement overhead, but, to the contrary, is simply composed of hinged or articulated sections that fold together upwardly into a compact position overhead. Furthermore, when the door is closed, practically the entire weight thereof is sustained at its lower edge, as the lower edge of the section 3 will rest on the floor or sill of the doorway because of the lost motion in the hinges 4, and in this way the door is tight all around when in closed position, and the slight space 19 at the upper edge of the section 1 is fully covered by the frame portion 20 of the doorway when the door is in closed position. Moreover, the invention is of such character that the door sections can be made of light wood, if desired, and do not necessarily have to be made of metal, although wood or metal, or other materials, can be employed, if desired. When properly balanced, very little effort is required to raise the door into open position, and very little effort is required to pull the door down into closed position.

It will be seen that the uppermost section 1 and the middle section 2 are hinged together to break joint inwardly, while the middle and lowermost sections are hinged together to break joint outwardly, whereby the outer sides of the uppermost and middle sections come together, whereas the inner sides of the middle section and the lowermost section come practically flatwise together, when the door is folded and in open position. The uppermost section 1, it will be seen, is hinged at its upper edge to the top of the doorway to swing inwardly and upwardly, and the counterbalancing means are effective to hold the sections folded tightly together and in overhead position when the door is open.

It will be seen that the point of attachment or engagement 14 of the counterbalancing means 13 with the lowermost section 3 is movable toward and away from the vertical plane

of the door during the motion of the door in closing and opening, whereby this point 14 is some distance inside of the vertical plane of the door, when the door is in fully opened position. In this way, the point of attachment or engagement 14 assumes the position by which it advantageously supports the weight of all three sections in raised position, and prevents the lowermost section from sagging downwardly when the door is fully open. Thus, the counterbalancing means is attached only to the lowermost section of the door, and such means is sufficient to support the entire door in raised position. The lowermost edge of the door is releasable from the vertical plane of the door, and is free when the door is in fully opened position, for the reasons and in the manner explained.

When the door is open, it will be seen that the sections 1, 2 and 3 are entirely inside the doorway, in a safe and dry place overhead, so that they will not be outside and will not catch rain or snow, when the door is open.

In effect, therefore, the flexible connections 13 are connected only to the lowermost section 3, in the sense that while these connections control the sections 1 and 2, it is nevertheless true that they only do this through the medium of the hinges between the sections. In other words, these flexible counterbalancing connections are so attached that they control the lowermost section directly, and only control the other sections through the medium of said hinges.

What I claim as my invention is:

1. A door construction comprising a plurality of vertically disposed and hinged or articulated sections all mounted to fold upwardly together into a final overhead open position at the top of the doorway, having means whereby a lower section is movable upwardly a distance in the vertical plane thereof, in the operation of opening the door, and is movable downward in said plane in the closing of the door, the lowermost edge of the door being releasable from said plane and being free when the door is folded and fully open.

2. A structure as specified in claim 1, comprising counterbalancing means connected to said lower section to assist in lifting and folding the door upwardly into open position, with the lower edge of said lower section free and inside the building.

3. A structure as specified in claim 1, comprising vertically disposed guides at the sides of the doorway, with means at the joint between two of the sections for engaging said guides, inner and outer door-jambs, the inner door-jambs being of less height than the lowermost section of the door, when the door is in closed position, whereby the said lowermost section is releasable from the door-jambs to permit upward folding of the door sections, and permitting

unfolding of the sections and re-entrance of the lower section between said inner and outer jambs, together with counterbalancing means attached to the lowermost section.

4. A structure as specified in claim 1, comprising vertically disposed guides at the sides of the doorway, with means at the joint between two of the sections for engaging said guides, inner and outer door-jambs, the inner door-jambs being of less height than the lowermost section of the door, when the door is in closed position, whereby the said lowermost section is releasable from the door-jambs to permit upward folding of the door sections, and permitting unfolding of the sections and re-entrance of the lower section between said inner and outer jambs, together with counterbalancing means attached to the lowermost section, there being three of said sections, the uppermost and the middle sections being hinged to break joint inwardly, and the middle and the lowermost sections being hinged to break joint outwardly, when the door is opened, and the uppermost section having its upper edge portion hinged to the top of the doorway in a manner permitting the uppermost section to swing inwardly and upwardly, but the outer door-jamb holding the sections against outward movement and in the same plane when the door is in closed position.

5. A structure as specified in claim 1, there being three of said sections, the uppermost section being hinged at its upper edge to the top of the doorway in a manner permitting this section to swing inwardly and upwardly, the middle section and the uppermost section being hinged together to break joint inwardly, the middle section and the lowermost section being hinged together to break joint outwardly, and inner and outer door jambs holding said lowermost section in a vertical plane during the initial opening movement of the door, as well as during the final closing movement thereof.

6. A structure as specified in claim 1, there being three of said sections, the uppermost section being hinged at its upper edge to the top of the doorway in a manner permitting this section to swing inwardly and upwardly, the middle section and the uppermost section being hinged together to break joint inwardly, the middle section and the lowermost section being hinged together to break joint outwardly, and inner and outer door jambs holding said lowermost section in a vertical plane during the initial opening movement of the door, as well as during the final closing movement thereof, together with counterbalancing means attached to said lowermost section, serving to hold the sections folded tightly together in overhead position.

7. A door construction comprising a plurality of vertically disposed and hinged or articulated sections mounted to fold up-

wardly together into an overhead position at the top of the doorway, comprising vertically disposed guides at the sides of the doorway, with means on the joint between two of the sections for engaging said guides, inner and outer door-jambs, the inner door-jambs being of less height than the lowermost section of the door, when the door is in closed position, whereby the said lowermost section is releasable from the door-jambs to permit upward folding of the door sections, and permitting unfolding of the sections and re-entrance of the lower section between said inner and outer jambs, together with counterbalancing means attached to the lowermost section.

8. A door construction comprising a plurality of vertically disposed and hinged or articulated sections mounted to fold upwardly together into an overhead position at the top of the doorway, comprising vertically disposed guides at the sides of the doorway, with means on the joint between two of the sections for engaging said guides, inner and outer door-jambs, the inner door-jambs being of less height than the lowermost section of the door, when the door is in closed position, whereby the said lowermost section is releasable from the door-jambs to permit upward folding of the door sections, and permitting unfolding of the sections and re-entrance of the lower section between said inner and outer jambs, together with counterbalancing means attached to the lowermost section, there being three of said sections, the uppermost and the middle sections being hinged to break joint inwardly, and the middle and the lowermost sections being hinged to break joint outwardly, when the door is opened, and the uppermost section having its upper edge portion hinged to the top of the doorway in a manner permitting the uppermost section to swing inwardly and upwardly, but the outer door-jamb holding the sections against outward movement and in the same plane when the door is in closed position.

9. A door construction comprising a plurality of vertically disposed and hinged or articulated sections mounted to fold upwardly together into an overhead position at the top of the doorway, there being three of said sections, the uppermost section being hinged at its upper edge to the top of the doorway in a manner permitting this section to swing inwardly and upwardly, the middle section and the uppermost section being hinged together to break joint inwardly, the middle section and the lowermost section being hinged together to break joint outwardly, and means holding said lowermost section in a vertical plane during a portion of the opening movement of the door, as well as during a portion of the closing movement thereof.

10. A door construction comprising a plurality of vertically disposed and hinged or articulated sections mounted to fold upwardly together into an overhead position at the top of the doorway, there being three of said sections, the uppermost section being hinged at its upper edge to the top of the doorway in a manner permitting this section to swing inwardly and upwardly, the middle section and the uppermost section being hinged together to break joint inwardly, the middle section and the lowermost section being hinged together to break joint outwardly, means holding said lowermost section in a vertical plane during a portion of the opening movement of the door, as well as during a portion of the closing movement thereof, and counterbalancing means attached in effect to said lowermost section, serving to hold the sections folded tightly together in overhead position.

11. A door construction comprising a plurality of vertically disposed and hinged or articulated sections mounted to fold upwardly together into an overhead position at the top of the doorway, and counterbalancing means attached in effect only to the lowermost hinged section of the door, the point of attachment of said lowermost section being movable toward and away from the vertical plane of the door, by the opening and closing motion of the door, whereby said point of attachment is a distance inside of said plane when the door is in raised position, to provide leverage to hold the door in raised position with the lower edge of said lowermost section free and inside the building.

12. An overhead vertical door comprising upper and lower sections and an intermediate section hinged together, guiding means extending vertically at each side of the door, and counterbalancing means having engagement with the lower hinged section to support all of the sections in raised position, the point of support of said counterbalancing means on said lower section being movable away from the vertical plane of the door and said guiding means when the door is folded into final open position, thereby to support the sections in raised position, to provide leverage to hold the door in raised position, with the lower edge of said lower section free and inside the building.

13. A structure as specified in claim 1, said lowermost edge being the lower edge of said lower section of the door, and this lower section having its said free edge inside the building when the door is in overhead open position, and having its upper edge practically retained in said vertical plane when the door is in said open position.

14. A door construction comprising a plurality of vertically disposed and hinged or articulated sections mounted to fold upwardly together into an overhead position at the

top of the doorway, comprising hinges between sections to break joint inwardly, other hinges between sections to break joint outwardly, whereby the outer sides of some sections fold together, and some sections fold with their inner sides together, with all of the sections when folded together as stated fully inside of the doorway when the door is in overhead open position, counterbalancing means attached in effect to the lowermost section of the door to counterbalance the weight of all the sections in raised position, and means requiring vertical motion of the lowermost section in the vertical plane thereof in opening the door before this section can be swung into folded position.

15. A structure as specified in claim 14, the uppermost section having pivotal connections at the upper corners thereof, with some lost motion vertically in said pivotal connections.

16. A structure as specified in claim 14, said sections having horizontal edges adapted to fit tightly together when the door is in vertical closed position, and the uppermost section having pivotal connections at the upper corners thereof, with some lost motion vertically in said pivotal connections.

17. A structure as specified in claim 14, said counterbalancing means comprising flexible connections attached in effect to the lowermost section of the door only, whereby said counterbalancing means control the other sections only through the medium of the hinges between the sections.

Specification signed this 1st day of November, 1928.
